UNITED STATES PATENT OFFICE.

GEORGE WALKER, OF NEWTON, MASSACHUSETTS.

SHIP'S INSTRUMENT.

Application filed August 23, 1919. Serial No. 319,392.

This invention relates to a ship's instrument for counting during predetermined periods of time, such as each minute, the number of revolutions of each propeller and 5 the average number of revolutions of all the propellers, and for automatically measuring and indicating the distance travelled by the ship whether at constant or varying speeds.

10 In my former application for Letters Patent of the United States Serial No. 273,744, filed January 29, 1919, an instrument is shown which indicates on suitable dials, for predetermined intervals of time 15 (as each minute), the exact number of revolutions of each propeller and the average number of revolutions of all the propellers.

My said former instrument also indicates the number of miles the ship has travelled, 20 determined by the number of propeller revolutions (average) required to drive the ship a mile at given propeller speeds. To accomplish this however a governor arm or hand must be manually adjusted for every dif- 25 ferent propeller speed to correspond to the number of propeller revolutions required to drive the ship a mile at that speed. So long as the given propeller speed at which the governor arm is set is accurately maintained 30 the instrument will correctly register the distance travelled; but if the given propeller speed is not maintained the distance indicator will not correctly register the distance travelled. For example, if a particular ship 35 is driven 10 knots per hour, at a propeller speed of 148 revolutions per minute the propeller revolutions will be 888 per knot.

With my former instrument the governor hand would be set at 888 and the distance 40 travelled would then be accurately registered so long as the speed of 148 revolutions per minute is maintained. As a practical matter however it is difficult if not impossible to maintain a propeller speed of exactly the 45 number of revolutions per minute ordered, and in the example assumed if the propeller speed varied from 148 R. P. M. by even a very slight amount the distance travelled would vary and the instrument set for exactly 50 148 R. P. M. would record the distance incorrectly.

Not only will an instrument working according to the principle set forth in my said former application fail to register correctly if the speed varies, but even if a constant 55 and correct speed is maintained it is a disadvantage to be obliged manually to set the governor hand in accordance with the number of revolutions per mile at every change 60 of speed.

In my present instrument, instead of controlling the distance indicator by the number of propeller revolutions per mile, the distance indicator is controlled by the number of propeller revolutions per minute, that is, 65 by the propeller speed. This instrument will automatically and accurately register the actual distance the ship has travelled, whether at constant or varying speeds, and without 70 manual adjustment of any kind to adapt the instrument to different propeller speeds.

In the accompanying drawings which illustrate the invention,—

Figure 1 is a diagrammatic view showing 75 the electrical connections;

Figure 2 is a sectional view on a plane through line 2—2 of Fig. 3 looking in the direction of the arrows, and showing the mechanism of the instrument in side elevation, certain parts being omitted for the sake 80 of clearness;

Figure 10 is a plan view of the lower average revolution counter dial. 100

S and P (Fig. 1) indicate respectively the

starboard and port propeller shafts of a vessel having two propellers. The propeller shafts carry respectively insulating rings 1 and 1', having contact pieces 2 and 2'. Each 5 revolution of starboard propeller shafts S will connect contacts a' b' through contact piece 2 thereby energizing electro-magnet 3 through the circuit including a, b, and switch 72, connecting the main lead lines A 10 and B, which are supplied with current from any suitable source of electrical energy.

Similarly each revolution of port propeller shaft P will energize electro-magnet 3' through the circuits including conductor 15 c, contacts c', 2', d', and conductor d, connecting lines A and B.

Each time electro-magnet 3 is energized it operates arm 4 (Figs. 2, 3 and 7) which is connected to the armature of the magnet 20 and is pivoted on a stud 5 fixed to the base plate of the casing or frame. The arm 4 is held on the stud by a collar 6 (Fig. 7) fastened to the stud. A spring tends to pull the arm 4 away from the magnet, and a 25 stud 7 mounted on the base plate acts as a stop to limit the movement of the arm in that direction. At the free end of the arm 4 is an oscillating pawl 8 pivoted on stud 9.

30 The pawl 8 engages and actuates a ratchet wheel 10 fastened solidly to a rotatable shaft 11. Shaft 11 (Figs. 2, 3, 4, 5 and 7) turns at its lower end on the base plate of the casing, and at its upper end in plate X, 35 through which the shaft extends. Fixed to the same shaft 11 with ratchet wheel 10 and turning therewith is a gear wheel 12 (Fig. 5). 13 (Figs. 5 and 7) is an oscillating arm pivoted on shaft 11 and normally 40 urged to the left, that is, toward gear 17, by a spring 14 fastened to plate X. Gear wheel 15, a duplicate of gear wheel 12, is journaled on arm 13 by a stud 16, and is permanently in mesh with gear wheel 12. 45 Gear wheel 17, identical with gear wheels 12 and 15, is fixed to a revolving shaft 18, which turns at one end in plate X and at the other end in a supporting bracket 19 fastened to plate X. A heart shaped cam 50 20, forming part of the resetting mechanism is fixed to gear wheel 17, and a hand or pointer 21 (Fig. 6) is fixed to the end of shaft 18.

From the foregoing it will be seen that 55 each time electro-magnet 3 is energized by one revolution of the propeller shaft S, with gears 15 and 17 in engagement, ratchet wheel 10 will be revolved the distance of one tooth, and wheel 10 acting through 60 shaft 11, gear wheel 12, gear wheel 15, gear wheel 17 and shaft 18 with turn hand 21 on dial D¹.

Similarly hand 21^A on dial D² will be operated through gear wheels 15^A and 17^A and 65 shaft 18^A, when gears 15^A and 17^A are in

mesh. The parts 13^A, 14^A, 15^A, 16^A, 17^A, 18^A, 19^A and 20^A are identical with the corresponding parts numbered 13 to 20 through which the hand 21 is operated.

If the pair of gears 15 and 17, and the 70 pair of gears 15^A and 17^A, are alternately engaged and disengaged at predetermined intervals of time, say each minute, the number of revolutions of the starboard propeller shaft for the successive predetermined periods of time will be alternately indicated on dials D¹ and D², which will show minute by minute (or other predetermined period) the propeller speed, the revolution counter mechanism for each dial ceasing to operate 75 the instant the other begins to operate.

By precisely similar mechanism the port propeller shaft P actuates the hands 21' and 21^A' on the pair of revolution counter dials D³ and D⁴ for the port propeller, 80 through electromagnet 3', ratchet wheel 10', shaft 11', and mechanism (not shown) identical with that in Fig. 5. The parts 4', 5', 6', 7', 8', 9', 10', 11', 18', and 18^A' are like the corresponding parts 4, 5 etc. already described. Thus the speed of the port propeller will be indicated minute by minute 85 (or other predetermined period) on the dials D³ and D⁴ alternately.

To obtain the average speed of the two 90 propellers, revolution counter mechanism (not shown) identical with that shown in Fig. 5 is provided between the pair of revolution counters for the starboard propeller and the pair for the port propeller. The average revolution counter mechanism actuates alternately the hand 21'' on the upper dial D⁵ and the hand 21^A'' on the lower dial D⁶. The central shaft 51 (Figs. 2, 4 and 7) corresponds to shaft 11 and acting 95 through mechanism like that shown in Fig. 5 alternately drives the average speed indicator hands 21'' and 21^A'' in the same manner as already described.

Shaft 51 is rotated at the average speed of the shafts 11 and 11' by the following means:—Gear wheels 46 and 46' (Figs. 2, 4 and 7) fast on shafts 11 and 11' respectively mesh with gear wheels 46^A and 46^A'. Gear wheel 46^A meshes with gear wheel 47 loose on shaft 51, and gear wheel 46^A' meshes with gear wheel 47' loose on shaft 51. Bevel gears 48 and 48' are fixed respectively to gears 47 and 47'. Between the bevel gears 48 and 48' and meshing therewith is a bevel pinion 49 carried by arm 50 which is fast on shaft 51. The differential gearing thus provided will cause the shaft 51 to rotate at the average speed of the shafts 11 and 11'. The index hands 21'' and 21^A'' will therefore indicate the average revolutions 100 of the starboard and port propellers.

By way of illustration and not of limitation I have shown dials D¹, D² etc. having scales to indicate 480 propeller revolutions, 105 110 115 120 125 130

whereby the instrument is adapted for use on any ship having a propeller speed not exceeding 480 revolutions per minute. Under the assumed conditions the ratchet wheels 10 and 10' will also have 480 teeth, and the ratchet wheels 10 and 10' and consequently the hands 21 or 21^A, and 21' or 21^A, will be turned 1/480 of a revolution at each complete revolution of the propeller.

10 It is to be understood however that the number of ratchet teeth and of the scale indications on the dials might be greater or smaller without departing from the principle of the invention, thereby adapting the instrument for use on ships having a different maximum propeller speed from that assumed for the purpose of illustration.

15 I will now describe the mechanism by which the two revolution counter mechanisms of a pair are alternately engaged and disengaged, and reset to zero or initial position ready to start again.

20 Referring to Fig. 5, gear 12, which is at all times in operative condition, will be turned in a clockwise direction by electromagnet 3. Gears 15 and 15^A, carried by arms 13 and 13^A, are always in mesh with gear 12. Springs 14 and 14^A acting on arms 25 13 and 13^A, respectively, tend to urge gears 15 and 15^A into engagement with gears 17 and 17^A respectively. Ratchet wheel 27 mounted on plate X is provided with a series 30 of spaced lugs 28 which act on the end of arm 13 and alternately lift gear wheel 15 out of mesh with gear wheel 17, and allow it to engage gear wheel 17 as the ratchet 27 is revolved in a counter-clockwise direction. The ratchet wheel 27 is turned by a pawl 35 29, pivoted by a pin 30 on bar 31. Bar 31 extends across the instrument and has a similar pawl 29 for each of the revolution counter mechanisms, acting on a similar ratchet 27 in each set for controlling the hands of the upper dials, namely dials D¹, 40 D³ and D⁵, of each pair. When the end of arm 13 rests on one of the lugs 28 gears 15 and 17 will be disengaged and therefore the hand 21 will be inoperative; but when the end of arm 13 drops off from the lugs 28 45 the gears 15 and 17 will engage, and the gear 17 and hand 21 will be turned from gear 12.

50 The revolution counter is reset to its zero or initial position after being disconnected from gear 15 through heart cam 20 which is fast on gear wheel 17. Arm 23 by pressing upon heart cam 20 in any position of the latter will automatically turn it, together with the gear wheel 17 and hand 21, to the position shown which is zero or starting position. The action of the heart cam is in accordance with the well known principle of a stop watch. The arm 23 is pivoted to the plate X at 22 and is pressed 55 toward the heart cam by a spring 25. A

projection or tooth 23' on the side of arm 23 is engaged and disengaged by the lugs 28 on ratchet wheel 27, alternately to lift the arm away from the cam and to allow the arm to act on the cam as the ratchet 27 70 revolves. Similarly a brake arm 24 is controlled by the lugs 28 acting on a projection on the brake arm, alternately to hold the wheel 17 from turning and to release it. Spring 26 normally tends to force arm 24 75 against gear wheel 17.

The lugs 28 are spaced on ratchet wheel 27 with relation to the teeth to act as herein-after described, and the bar 31 has an end-wise movement to the right sufficient for 80 the pawl 29 to turn the ratchet wheel 27 the distance of one tooth.

Assuming the parts to be in the position shown in Fig. 5 and the instrument to be in operation, the hand 21 will be in zero position and the gear wheel 12 will be revolving step by step in a clockwise direction but out of engagement with gear wheel 17.

85 If now bar 31 is shifted once to the right, ratchet wheel 27 will be turned the distance 80 of one tooth and the following actions will take place simultaneously:—Arm 13 will drop off from a lug 28 thus throwing gear wheel 15 into mesh with gear wheel 17; gear wheel 17 and consequently hand 21 will start to turn in a clockwise direction; arm 23 will be lifted out of contact with heart cam 20 by one of the lugs 28; and brake arm 24 slides along the face of a lug 28 and is still held out of contact with gear wheel 17. 100

If now bar 31 is again shifted to the right the following actions will simultaneously occur:—A lug 28 will engage the end of arm 13 and lift gear wheel 15 out of contact with gear wheel 17; arm 23 will ride along the face of a lug 28 and remain in elevated position out of contact with heart cam 20; and brake arm 24 will drop off from a lug 28 and press against gear wheel 17 holding it against movement. This will 105 stop hand 21 of dial D¹ and lock it in the position in which it was stopped. 110

If now a third movement to the right is given to bar 31 the following actions will simultaneously take place:—Arm 13 will ride along the face of a lug 28 holding gear wheel 15 out of engagement with gear wheel 17; arm 24 will be lifted by a lug 28 to release gear wheel 17; and arm 23 will drop off from a lug 28 and strike heart cam 20, returning gear wheel 17, and with it hand 21, to their zero or initial position, and locking them in that position. 115

120 Inasmuch as bar 31 carries an actuating pawl 29 associated with all the upper revolution counter mechanisms which control the hands 21, 21', and 21'' of dials D¹, D³, and D⁵, it will be seen that all of these parts will be started, stopped and reset in unison by 125 the movements of bar 31. 130

In like manner the lower set of revolution counter mechanisms of the several pairs, together with the hands 21^A, 21^{A'}, and 21^{A''}, on dials D², D⁴ and D⁶ are controlled by the movements of bar 31^A, which is shifted to the left for its operating stroke. The parts 22^A, 23^A, 24^A, 25^A, 26^A, 27^A, 28^A, 29^A, 30^A, and 31^A, are the same in construction and operation as the corresponding parts 22, 23, etc. 10 already described.

The bar 31 is operated to start, stop and reset the revolution counter mechanisms at predetermined intervals by automatic means, under the control of a chronometer 38 (Fig. 15 1). Arm 33 (Figs. 2 and 7) which shifts bar 31, carries the armature of electro-magnet 37 by which it is actuated. Electro-magnet 37 is energized at the desired intervals of time by the closing of circuits controlled by the chronometer. 20

The chronometer hand 39 will make one complete revolution in two minutes, or one-half a revolution in one minute. Thus it will move from contact point 40 to contact 25 point 41, or from point 41 to 40, in one minute. It will be understood that the period of one minute is used merely for illustration and because it is used to reckon propeller speed by the number of revolutions 30 per minute, but the chronometer might be designed to measure any other predetermined period of time desired.

Assuming that the index hands of the revolution indicators D¹, D³, D⁵ are at zero position, if the chronometer hand 39 makes contact with point 40, magnet 37 will be energized through the circuit comprising e and f connected to main line A, and hand 39, line g and switch 72, connected to main line 40 B. Thereupon magnet 37 actuates arm 33 which shifts bar 31 to the right, and starts the upper set of revolution counter mechanisms as already explained. At the end of one minute, hand 39 will touch contact point 45 41', which also is connected through line f with magnet 37, and will again energize the magnet thereby stopping the upper set of revolution counter mechanisms, leaving the indicator hands 21, 21' and 21'' registering 50 the actual number of revolutions of each propeller, and the average revolutions of both propellers, during the minute just elapsed. At any time during the next minute the upper revolution counters may be reset to their initial position ready to start again, but I prefer to leave the indicator hands at rest until just before the expiration of the next minute so that the dials will show during approximately the whole of each 55 minute the propeller revolutions for the next preceding minute, thus affording ample time for observing the readings. When the chronometer hand 39 reaches contact point 60 42, which may be, say, at the expiration of

59 seconds, electromagnet 37 will again be energized, (42 being also connected to line e) and bar 31 will again be shifted thereby resetting the revolution counter to zero or initial position. Almost immediately chronometer hand 39 will again touch contact 70 point 40 at the end of the second minute, thus completing the cycle and again starting the revolution counters of the upper set. 75

In like manner the lower set of revolution counters associated with dials, D², D⁴ and D⁶, are operated alternately with the revolution counters of the upper set. Starting with the index hands 21^A, 21^{A'}, and 21^{A''} at zero, when chronometer hand 39 touches contact point 41 (at the same instant it stops the upper set of revolution counters), electromagnet 37^A is energized through the circuit including h and j, thereby swinging arm 33^A (Fig. 2), shifting bar 31^A to the left, and starting the lower set of revolution counters. At the end of one minute the hand 39 will touch contact point 40' and again close a circuit through electro-magnet 37^A, through lines i and j, thus stopping the revolution counters 80 of the lower set at the same instant when the counters of the upper set are started. And just before the expiration of the next minute the hand 39 will touch contact point 45 thus closing the circuit h, h and j through electro-magnet 37^A and resetting the lower set of 85 revolution counters. At the end of the minute the hand 39 reaches contact point 41 completing the cycle and again starting the revolution counters of the lower set simultaneously with the stopping of the upper set. 90

The bars 31 and 31^A may be manually operated by push pins 32 and 32^A mounted to slide in the wall of the casing (Figs. 2, 5, 6 and 9). 95

100

Distance indicator.

As already stated the revolution indicator dials of the instrument herein described and illustrated in the drawings have 480 scale 110 graduations. The instrument is thus appropriate for any ship having a maximum of 480 propeller revolutions, or less, per minute (or other predetermined period of time). The dials may show any number of 115 graduations desired provided the ratchet wheels and gears are proportioned to correspond, but a scale of 480 graduations is selected as a convenient example because suitable for a class of modern destroyers of the 120 United States Navy having a maximum propeller speed of about 470 revolutions per minute. 125

The problem and its solution, of providing a distance indicator controlled by the propeller speed to show the actual distance in nautical miles a ship has travelled, can best be explained by a concrete example. The

following is the actual speed table of a U. S. war vessel:

Speed knots	Revolu- tions per minute	Miles (nautical) per minute	Revolu- tions per 1/100 of a knot
10	5	.74	.0833
	6	.88	.10
	7	.103	.1166
	8	.118	.1333
	9	.133	.15
	10	.148	.1666
	11	.162	.1833
	12	.175	.20
	13	.188	.2166
	14	.201	.2333
15	15	.214	.25
	16	.228	.2666
	17	.244	.283
	18	.261	.30
	19	.277	.3166
	20	.294	.3333
	21	.315	.35
			9.

20 If it is desired to run the ship at the rate for example of 10 knots per hour the order is given to drive the propellers at a speed of 148 revolutions per minute. This will drive the ship .16 2/3 nautical miles per minute. Or if the propellers turn 74 revolutions per minute the ship will travel at the rate of 5 knots per hour, and will travel .08 1/3 of a knot during the minute.

25 Referring now to Figs. 9 and 10 which show the average revolution counter dials, electrical contact points 53 are arranged on the dial in the path of the hands 21" and 21", spaced on the dial with relation to the scale graduations in accordance with the foregoing table. Thus, since 74 propeller revolutions per minute will drive the ship .08 1/3 of a mile (this being at the rate of 5 knots per hour) a contact point 53 is placed at graduation #74 on the dial. 30 Similarly contact points 53 are located about the dial to register each .01 of a knot travelled, and each .01 is again subdivided into thirds, so that the instrument will measure and register the distance the ship has travelled within 1/3 of 1/100 of a knot. If it is desired to measure the distance to a smaller fraction the subdivisions may be smaller by placing contact points 53 closer together, but for practical purposes, and by 35 way of illustration, it is sufficient to measure the distance travelled within 1/3 of 1/100 of a nautical mile, which is only about 20 feet. The contact points 53 of dial D⁵ are connected by electrical conductor 52 (Fig. 40 1) preferably located on the under side of the dial, and contact points 53 of dial D⁶ are connected by electrical conductor 52^A (Figs. 1 and 7). Conductor 52 is connected with main line A through electro-magnet 63, by lines l and m; and conductor 52^A is connected with main line A through electro-magnet 63 by lines o and m. As the hands 21" and 21" move around the face of the 45 dials they successively engage contact points 53 and energize electro-magnet 63 by which

the distance indicator 69 (Figs. 6 and 8) is actuated.

50 The distance indicator 69 is a counter of the well known Veeder type operated by the armature of electro-magnet 63 by a pawl and ratchet wheel of usual construction, the latter having teeth spaced to turn the first or right hand numeral wheel of the counter 1/30 of a revolution each time electro-magnet 63 is operated. Each of the numeral 55 wheels of the distance counter 69 carries on its periphery ten numerals, "0 to 9", as usual, so that each time the first or right hand numeral wheel is advanced it will register 1/3 of 1/100 of a knot. Any desired number of numeral wheels may be used, six being shown in the drawings, the four at the left indicating knots or nautical miles, and the two at the right indicating hundredths of knots. Thus the counter shown is adapted to register distance up to 9999.99 2/3 knots. To show the distance to 1/3 of 1/100 of a knot the space between centers on the periphery of the numeral wheel at the extreme right (the hundredth wheel) 90 may be divided by lines into thirds, to be observed in conjunction with a central line marked on the casing (Fig. 6).

95 A detail of the mechanism for operating the distance indicator is illustrated in Fig. 8. Ratchet wheel 68 has 30 teeth and is fast on shaft 73, which operates the distance indicator. Therefore each time ratchet wheel 68 turns the distance of one tooth it will rotate the right hand number wheel of the counter 69, one third of the distance between centers of its numerals. Ratchet wheel 68 is operated by pawl 67 carried on the end of arm 64. Arm 64 is pivoted at 66 and carries the armature 65 of electro-magnet 63. 100 Each time electro-magnet 63 is energized it will turn the ratchet 68 one tooth.

105 Suppose now that the propellers are turning 88 (average) revolutions per minute. The ship will then travel .10 of a knot during the minute, or at the rate of 6 knots per hour. The hand 21" in moving from zero to graduation 88, contacts successively with all the points 53 up to and including that located at graduation 88, each time advancing the distance indicator 69 one step so as to register 1/3 of 1/100 of a knot. Therefore the distance indicator will read 110 .10 knots at the end of the first minute at the assumed propeller speed. Accordingly as the propeller speed varies and engages a larger or smaller number of contact points 53 during the minute (or other predetermined period of time) a larger or smaller number of impulses will be given electro-magnet 63 and corresponding readings will appear on distance indicator 69.

115 Similarly the distance travelled during the next succeeding minute will be recorded on the distance indicator through the hand 120

21^{A''} of the lower dial D⁶, which closes the circuit o, m, (Fig. 1) through electro-magnet 63 by successively engaging contact points 53 on dial D⁶ which is identical with dial D⁵.

By this arrangement of contact points on the average revolution dials D⁵ and D⁶ the actual distance the ship travels minute by minute is continuously registered on the 10 distance indicator 69. The distance travelled during one minute is registered from the revolution counter mechanism associated with dial D⁵ and during the next minute from the revolution counter mechanism associated with dial D⁶, and so on alternately 15 and continuously; because the actual average revolutions of the propellers during each succeeding minute are counted by the revolution counters and by them translated into 20 distance on the distance indicator.

From the foregoing it will be clear that the instrument will record automatically and correctly the distance travelled at varying speeds. If, for example, the ship is building up its speed from 5 knots per hour, at 25 the rate of one knot each minute the distance indicator will show .08 1/3 knots at the end of the first minute (see the above table and Fig. 9), .18 1/3 knots (i. e. .08 30 1/3+.10) at the end of the second minute, .30 knots (i. e. .08 1/3+.10+.11 2/3) at the end of the third minute, and so on.

The mechanism for automatically placing the distance indicator alternately under the 35 control of the two revolution counters of the pair of average revolution counters (associated with dials D⁵ and D⁶) is as follows:— The circuits through hands 21^{''} and 21^{A''} and their respective contact points 53, are 40 controlled by electric switch 56 (Figs. 1, 3 and 4) the operation of which is controlled by chronometer 38 through electro-magnets 54 and 55. When chronometer hand 39 touches contact point 44, electro-magnet 54 45 will be energized through line s which is connected to main line A, thereby swinging switch 56 which carries armature 57, into engagement with contact point 61. This completes the circuit from main line B 50 through switch 56 and line n to hand 21^{''}. When chronometer hand 39 touches contact point 43, electro-magnet 55 will be energized through line r which is connected to main line A, thereby swinging switch 56, 55 which carries armature 57 into engagement with contact point 62. This completes the circuit from main line B through switch 56 and line p to hand 21^{A''}. A spring pressed arm 60 (Figs. 3 and 4) yieldingly holds the 60 switch 56 in either position.

As previously explained, when chronometer hand 39 touches contact 40, hand 21^{''} on dial D⁵ is started. At the same instant chronometer hand 39 engages contact 44 thus throwing switch 56 on to contact 61 and

closing the distance indicator operating circuit through hand 21^{''}. When chronometer hand 39 reaches contact 41 index hand 21^{''} is stopped and simultaneously index hand 21^{A''} is started. At the same instant hand 39 engages contact 41 it also touches contact 43, thereby swinging switch 56 from contact 61 to contact 62 and establishing the circuit through hand 21^{A''}. Therefore electro-magnet 63 is at all times under the control of either the hand 21^{''} or the hand 21^{A''}, and is continuously operated first by one revolution counter mechanism of the pair of average revolution counters and then by the other.

It will also be seen that when either hand 21^{''} or 21^{A''} are reset to zero position, the contact points 53 will be in an open circuit and therefore the passing of the hands backward over the contacts 53 will not affect 85 magnet 63.

The distance indicator 69 has a resetting shaft 70 (Fig. 6) provided with a knurled head 71, one revolution of which by hand 90 resets all the numeral wheels to zero in the usual way.

To start the instrument, switch 72 (Fig. 1) is opened. This breaks all electrical connections. Distance indicator 69 is manually reset to zero by one revolution of the resetting head 71 (Fig. 6). The revolution indicators are all reset to zero position by means of the hand operated pins 32 and 32^A (Figs. 2, 5 and 7) as previously described. The chronometer hand 39 (Fig. 1) is set at starting point on contacts 40 and 44. Switch 72 is then closed.

By the closing of switch 72 the instrument is started and all the revolution counters will start in unison, since chronometer hand 39 is on both contacts 40 and 44 and therefore energizes both magnets 37 and 37^A thus starting both the upper and lower sets of revolution counters and throws switch 56 onto contact 61. Pin 32^A is then manually operated once thus shifting bar 31^A once and the lower set of revolution counters will be stopped. From now on the operation of the instrument will be entirely automatic, for when chronometer hand 39 reaches contact 45 the hands of the lower set of revolution counters will be reset to zero, and when at the end of the first minute the hand 39 reaches contacts 41 and 43 the hands of the upper set of revolution counters will be stopped simultaneously with the starting of hands of the lower set and switch 56 will be thrown on to contact 62; and so on as already explained.

The expression "ship's instrument" wherever it occurs throughout the specification and claims is used to denote an instrument of the character described whether employed on water craft or air craft, as the principle of the invention is susceptible of adaptation

not only to steamships and other vessels driven by power, but to airplanes, dirigible balloons etc. driven by propelling means. Also the term "propeller" as herein used denotes the propelling means as a whole whether a single propeller or the average of a number of propellers, unless limited expressly or by the context to indicate a single unit of multiple propelling means.

10 In so far as the instrument is used merely to register on the distance indicator the distance travelled, the graduations on dials D^1 , D^2 etc. of the revolution counters might be omitted, in which case the hands or pointers 15 21 , 21^A , etc. merely become circuit closing members controlled by the propeller speed for controlling the distance indicator circuits through contacts 53 . Or, circuit closing arms or members other than the pointers 21 , 21^A , etc. might be provided for engaging contact points arranged elsewhere than on the dials, without departing from the principle of the invention.

15 It is also within the scope of the invention 25 to use spaced controlling elements other than electrical contacts (53).

The disks D^5 , D^6 , carrying the contacts 53 may be made removable and interchangeable with other disks having differently spaced contacts calibrated according to the speed table of another ship, so that the same instrument may be used for different ships by merely changing the average speed dials. Moreover provision for interchanging the 35 average speed dials on the same ship may be of importance. It is well known that the distance a ship will be driven by a certain number of propeller revolutions per minute varies with external conditions of the hull, 40 load or displacement, etc., more revolutions being required when the hull is foul, or when the vessel is loaded. A number of average speed dials may be carried having contact points calibrated according to varying conditions, and by using the appropriate dials 45 the instrument will correctly register the distance travelled under various conditions.

From the foregoing it will be evident that the present invention is characterized by 50 mechanism having regular cycles of operation during predetermined recurrent intervals of time (each of the contact members $21''$ and $21^{A''}$ completing their movements during successive minutes or other regular 55 intervals) and having means responsive to the speed of the propeller for regulating the movement of the mechanism (the movement of contact members $21''$ and $21^{A''}$ being automatically regulated both in rate and extent), thereby to measure the travel whether at the same or different speeds. Another unique characteristic of the invention is the 60 intermittent character of said mechanism (the contact members $21''$ and $21^{A''}$ stopping and starting at predetermined intervals), the

intermittent mechanism preferably being oscillatory in that it moves to and fro.

Obviously, instead of moving the contact members ($21''$ and $21^{A''}$) relatively to the irregularly distributed contacts (.01, .02, .03, etc) the contacts may be moved relatively to the contact members.

It will also be evident that the control means (rotary contacts 21 , distributed contacts 53 , etc., in the illustrated embodiment) 75 are so constructed that the movement of the distance indicating means (69 in the illustration) varies during each minute in accordance with the variations in ratio between propeller speed and distance traveled up to the current speed of the propeller. For example, if the speed of the propeller is 240 R. P. M., the distance indicator varies in speed during each minute in accordance with the variations in spacing between the contacts 53 from 0 up to 240 (see Fig. 9) and therefore in accordance with the variations in ratio between propeller speed and distance traveled up to 240 R. P. M., the current speed of the propeller. 90

I claim:

1. A ship's instrument comprising an indicator, and mechanism for successively advancing said indicator including a stationary part and a movable part, one of the parts having contacts distributed therealong recurrently to engage the other part to actuate said indicator, said contacts being distributed in accordance with the relation between the speed of the propeller, and the velocity of the ship throughout a predetermined range of propeller speeds.

2. Apparatus for measuring the distance travelled by a body driven by a propeller moving in a fluid medium, comprising controlling means movable according to the propeller motion during recurrent intervals, and indicating means movable in response to the controlling means, the movement of the latter means varying throughout each interval proportionately to the variations in ratio between propeller speed and distance travelled up to the current speed of the propeller.

3. A ship's instrument comprising a distance indicator, and mechanism controlled by the speed of the propeller during successive predetermined periods of time to measure on the distance indicator the distance the ship has been driven.

4. A ship's instrument comprising a distance indicator, and mechanism having regular cycles of operation during recurrent predetermined periods of time and controlled by the speed of the propeller automatically to measure on the distance indicator the distance the ship has been driven whether at constant or varying speeds.

5. A ship's instrument comprising a distance indicator and mechanism having

regular cycles of movement during successive predetermined periods of time, and means responsive to the propeller speed to regulate the rate of movement of said mechanism during each cycle, thereby to measure on the distance indicator the distance the ship has been driven whether at the same or different speeds.

6. A ship's instrument comprising a distance indicator, two controlling members therefor alternately actuated in proportion to the number of the propeller revolutions, and connections between said controlling members and said distance indicator adapted automatically and continuously to measure on the distance indicator the distance the ship has been driven whether at constant or varying propeller speed.

7. A ship's instrument comprising a revolution counter, a distance indicator, mechanism controlled by the revolutions of the propeller to indicate on the revolution counter the number of revolutions of the propeller, and mechanism having regular cycles of operation during successive predetermined periods of time and controlled by the speed of the propeller through the revolution counter adapted automatically to measure on the distance indicator the distance the ship has been driven whether at constant or varying propeller speed.

8. A ship's instrument comprising a distance indicator, two revolution counters for each of a plurality of propellers, alternately actuated by the revolutions of the propeller associated therewith and mechanism common to all of the propellers adapted automatically and continuously to measure on the distance indicator the distance the ship has been driven whether at constant or varying speed.

9. A ship's instrument comprising a distance indicator, two revolutions counters for each of a plurality of propellers, alternately actuated by the revolutions of the propeller associated therewith, two average revolution counters alternately actuated in proportion to the average of all the propellers, and mechanism controlled by the average revolution counters adapted automatically and continuously to measure on the distance indicator the distance the ship has been driven whether at constant or varying speed.

10. A ship's instrument comprising a distance indicator, two revolutions counters alternately actuated by the revolutions of the propeller, and mechanism controlled by the speed of the propeller through the revolution counters adapted automatically and continuously to measure on the distance indicator the distance the ship has been driven whether at constant or varying speed.

11. A ship's instrument comprising a revolution counter, a distance indicator, mechanism controlled by the revolutions of the

propeller to indicate on the revolution counter the number of revolutions of the propeller, and electrical mechanism controlled by the revolution counter for driving said indicator, said mechanism being arranged automatically to drive said indicator at a rate proportional to the number of revolutions required to drive the ship a predetermined distance at whatever speed the ship is being propelled.

12. A ship's instrument comprising a distance indicator, two controlling members therefor alternately actuated for predetermined periods of time in proportion to the number of the propeller revolutions, electrical mechanism including an electro-magnet for operating the distance indicator, and means to place said electro-magnet alternately under the control of said controlling members during their respective periods of operation, whereby said distance indicator will be continuously operated.

13. A ship's instrument comprising a distance indicator, two revolution counters alternately actuated for predetermined periods of time in proportion to the number of the propeller revolutions, electrical mechanism including an electro-magnet for operating the distance indicator, and means to place said electro-magnet alternately under the control of said revolution counters during their respective periods of operation, whereby said distance indicator will be continuously operated through said revolution counters.

14. A ship's instrument comprising a distance indicator, a controlling member therefor actuated in proportion to the number of the propeller revolutions, electrical mechanism including an electro-magnet for operating the distance indicator, and a series of electrical contacts in circuit with the electro-magnet engaged successively by the controlling member to operate the electro-magnet.

15. A ship's instrument comprising a distance indicator, mechanism controlled by the revolutions of the propeller to move proportionately to the number of revolutions of the propeller during a predetermined period of time, a series of stationary controlling elements therefor, and a movable controller actuated by the revolution controlled mechanism moving synchronously with the propeller revolutions adapted to cooperate with said stationary controlling elements successively, to operate the distance indicator, said stationary controlling elements being spaced to correspond to the distance the ship is driven during said predetermined period of time at constant or varying speed.

16. A ship's instrument comprising a distance indicator, mechanism controlled by the revolutions of the propeller to move proportionately to the number of revolutions of the

propeller during a predetermined period of time, electrical mechanism for operating the distance indicator, a series of electrical contacts therefor, and a controller actuated by the revolution controlled mechanism moving synchronously with the propeller revolutions adapted to engage said electrical contacts successively, to operate the distance indicator, said electrical contacts being spaced to correspond to the distance the ship is driven during said predetermined period of time at constant or varying speed.

17. A ship's instrument comprising a distance indicator, a revolution counter, mechanism controlled by the revolutions of the propeller to actuate the revolution counter proportionately to the number of revolutions of the propeller during a predetermined period of time, mechanism for operating the distance indicator, a series of stationary controlling elements therefor, and a movable controller actuated by the revolution counter mechanism moving synchronously with the propeller revolutions adapted to cooperate with said stationary controlling elements successively, to operate the distance indicator, said stationary controlling elements being spaced to correspond to the distance the ship is driven during said predetermined period of time at constant or varying speed.

18. A ship's instrument comprising a distance indicator, a revolution counter, mechanism controlled by the revolutions of the propeller to actuate the revolution counter proportionately to the number of revolutions of the propeller during a predetermined period of time, electrical mechanism for operating the distance indicator, a series of electrical contacts therefor, and a controller actuated by the revolution counter mechanism moving synchronously with the propeller revolutions adapted to engage said electrical contacts successively, to operate the distance indicator, said electrical contacts being spaced to correspond to the distance the ship is driven during said predetermined period of time at constant or varying speed.

19. A ship's instrument comprising a distance indicator, two controlling members therefor actuated alternately and proportionately to the number of revolutions of the propeller during predetermined periods of time, connections between said controlling members and said distance indicator to operate the latter, a chronometer, mechanism controlled by the chronometer to place said controlling members alternately in operative relationship to the propeller, and mechanism controlled by the chronometer to place said connections between the controlling members and the distance indicator alternately in operative condition.

20. Apparatus for measuring the distance traveled by a body driven by a propeller

moving in a fluid medium, comprising control members alternately movable according to the propeller motion, and indicating means movable in response to each movement of the control members, each movement of the latter means varying throughout its duration in accordance with the variations in ratio between propeller speed and distance traveled up to the current speed of the propeller.

21. A ship's instrument comprising a distance indicator, two revolution counters actuated alternately and proportionately to the number of revolutions of the propeller during predetermined periods of time, electrical connections between said revolution counters and said distance indicator to operate the latter, a chronometer, electrical mechanism controlled by the chronometer to place said revolution counters alternately in operative relationship to the propeller, and electrical mechanism controlled by the chronometer to place said connections between the revolution counters and the distance indicator alternately in operative condition.

22. A ship's instrument comprising a distance indicator, a revolution counter including a dial and hand, mechanism controlled by the revolutions of the propeller to actuate the hand proportionately to the number of revolutions of the propeller during a predetermined period of time, electrical mechanism for operating the distance indicator, and a series of electrical contacts on said dial adapted to be engaged successively by the hand, the operating circuit of said electrical mechanism including said hand and contacts, whereby the engagement of the hand with the contacts will operate the electrical mechanism which operates the distance indicator.

23. A ship's instrument comprising a distance indicator, mechanism controlled by the revolutions of the propeller to move proportionately to the number of revolutions of the propeller during a predetermined period of time, mechanism for operating the distance indicator including a removable member having a series of spaced controlling elements adapted to be interchanged with other similar members having differently spaced controlling elements, and a movable controller actuated by the revolution controlled mechanism moving synchronously with the propeller revolutions adapted to cooperate with said controlling elements successively, to operate the distance indicator.

24. A ship's instrument comprising a distance indicator, mechanism controlled by the revolutions of the propeller to move proportionately to the number of revolutions of the propeller during a predetermined period of time, electrical mechanism for operating the distance indicator including a removable member having a series of spaced

- electrical contacts adapted to be interchanged with other similar members having differently spaced electrical contacts, and a movable controller actuated by the revolution controlled mechanism moving synchronously with the propeller revolutions adapted to engage said electrical contacts successively, to operate said distance indicator.
25. A ship's instrument comprising a distance indicator, a revolution counter including a dial and hand, mechanism controlled by the revolutions of the propeller to actuate the hand proportionately to the number of revolutions of the propeller during a predetermined period of time, electrical mechanism for operating the distance indicator, and a series of electrical contacts on said dial adapted to be engaged successively by the hand, the operating circuit of said electrical mechanism including said hand and contacts, whereby the engagement of the hand with the contacts will operate the electrical mechanism which operates the distance indicator, said dial being removable and adapted to be interchanged with other similar dials having differently spaced series of electrical contacts.
26. A ship's instrument comprising speed-controlled mechanism controlled by the revolutions of the propeller to move proportionately to the number of revolutions of the propeller during a predetermined period of time, two movable members associated with and operated by said speed-controlled mechanism, automatic means for alternately connecting and disconnecting said movable members to and from said mechanism at predetermined intervals of time and a distance indicator alternately controlled by said members.
27. A ship's instrument comprising speed-controlled mechanism controlled by the revolutions of the propeller to move proportionately to the number of revolutions of the propeller during a predetermined period of time, two movable members associated with and operated by said speed-controlled mechanism, automatic means for alternately connecting and disconnecting said movable members to and from said speed-controlled mechanism, means for automatically resetting said movable members to their initial position after being disconnected from said speed controlled mechanism and a distance indicator alternately controlled by said members.
28. A ship's instrument comprising speed-controlled mechanism controlled by the revolutions of the propeller to move proportionately to the number of revolutions of the propeller during a predetermined period of time, two movable members associated with and operated by said speed-controlled mechanism, automatic means for alternately connecting and disconnecting said movable members to and from said speed-controlled mechanism, means for automatically resetting said movable members to their initial position after being disconnected from said speed controlled mechanism and a distance indicator alternately controlled by said members.
29. A ship's instrument comprising speed-controlled mechanism controlled by the revolutions of the propeller to move proportionately to the number of revolutions of the propeller during a predetermined period of time, two movable members associated with and operated by said speed-controlled mechanism, and automatic means for alternately connecting and disconnecting said movable members to and from said speed-controlled mechanism, and means for automatically operating said means at recurrent intervals and a distance indicator alternately controlled by said members.
30. A ship's instrument comprising a distance indicator, mechanism intermittently movable throughout equal succeeding periods of time, and means controlled by the speed of the propeller to regulate the extent of said movement, thereby to measure on the distance indicator the distance the ship has been driven whether at the same or different speeds.
31. In a ship's instrument, travel indicating mechanism controlled by the ship's propeller, said mechanism including means recurrently operative during equal periods of time irrespective of the rate of travel, an indicator controlled by said means, and means responsive to the speed of the propeller for automatically regulating the movement of said means during said periods to indicate the travel whether at the same or different speeds.
32. In a ship's instrument, travel indicating mechanism controlled by the ship's propeller, said mechanism including oscillatory means moving in one direction during equal periods of time irrespective of the rate of travel, an indicator controlled by said means, and means responsive to the speed of the propeller for automatically regulating the movement of said means during said periods to indicate the travel whether at the same or different speeds.
33. A ship's instrument comprising a distance indicator, and intermittent mechanism having regular periods of operation throughout varying speeds of the ship and controlled by the speed of the propeller automatically to measure on the distance indicator the distance the ship has been driven whether at constant or varying propeller speeds.
34. A ship's instrument comprising a distance indicator, mechanism intermittently

movable throughout equal succeeding periods of time, and means controlled by the speed of the propeller to regulate the rate of said movement, thereby to measure on the distance indicator the distance the ship has been driven whether at the same or different speeds.

35. A ship's instrument comprising a distance indicator, electrical mechanism for operating the distance indicator including a controlling member and a member having a series of contacts, and means for moving one of said members to cause said controlling member to engage said contacts successively.

36. A ship's instrument comprising a distance indicator, mechanism controlled by the revolutions of the propeller to move proportionately to the number of revolutions of the propeller during a predetermined period of time, a series of controlling elements and a controller adapted to cooperate with the controlling elements successively, to operate the distance indicator, said controlling elements and said controller being movable relatively to each other in response to said first mechanism and said controlling elements being spaced to correspond to the distance the ship is driven during said predetermined period of time at constant or varying speed.

37. A ship's instrument comprising a distance indicator, mechanism controlled by the revolutions of the propeller to move proportionately to the number of revolutions of the propeller during a predetermined period of time, electrical mechanism for operating the distance indicator, a series of electrical contacts therefor, and a controller adapted to engage said electrical contacts successively, to operate the distance indicator, said electrical contacts and said controller being relatively movable in proportion to the propeller revolutions and said electrical contacts being spaced to correspond to the distance the ship is driven during said predetermined period of time at constant or varying speed.

38. A ship's instrument comprising a distance indicator, a revolution counter, mechanism controlled by the revolutions of the propeller to actuate the revolution counter proportionately to the number of revolutions of the propeller during a predetermined period of time, mechanism for operating the distance indicator, a series of controlling elements therefor and a controller adapted to cooperate with the controlling elements successively, to operate the distance indicator, said controlling elements and controller being relatively movable in response to the revolution counter mechanism and said controlling elements being spaced to correspond to the distance the ship is driven during said predetermined period of time at constant or varying speed.

39. A ship's instrument comprising a distance indicator, a revolution counter, mechanism controlled by the revolutions of the propeller to actuate the revolution counter proportionately to the number of revolutions of the propeller during a predetermined period of time, electrical mechanism for operating the distance indicator, a series of electrical contacts therefor, and a controller adapted to engage said electrical contacts successively, to operate the distance indicator, said electrical contacts and controller being relatively movable synchronously with the propeller revolutions and said electrical contacts being spaced to correspond to the distance the ship is driven during said predetermined period of time at constant or varying speed.

40. A ship's instrument comprising a distance indicator, mechanism controlled by the revolutions of the propeller to move proportionately to the number of revolutions of the propeller during a predetermined period of time, mechanism for operating the distance indicator including a removable member having a series of spaced controlling elements adapted to be interchanged with other similar members having differently spaced controlling elements, and a controller adapted to cooperate with said controlling elements successively to operate the distance indicator, the controlling elements and controller being relatively movable synchronously with the propeller revolutions.

41. A ship's instrument comprising a distance indicator, mechanism controlled by the revolutions of the propeller to move proportionately to the number of revolutions of the propeller during a predetermined period of time, electrical mechanism for operating the distance indicator including a removable member having a series of spaced electrical contacts adapted to be interchanged with other similar members having differently spaced electrical contacts, and a controller adapted to cooperate with said controlling elements successively to operate the distance indicator, the controlling elements and controller being relatively movable synchronously with the propeller revolutions.

42. A ship's instrument comprising an indicator and mechanism for actuating said indicator including relatively movable electrical parts, one of the parts having electrical contact elements distributed in accordance with the relation between the speed of the propeller and the velocity of the ship throughout a predetermined range of propeller speeds, and means for producing relative movement between said parts in accordance with the propeller speed.

43. In a ship's instrument an indicator, means including an electromagnet for operating said indicator, a branched circuit

leading to said electromagnet, means in each branch for intermittently closing the circuit to said electromagnet, said means being controlled by the speed of the ship's propeller, and means for rendering either of said circuit closing means operative.

44. Apparatus for measuring the distance traveled by a body driven by a propeller moving in a fluid medium, comprising control means including rotary members advancing from the same initial position during alternate intervals of time, and common indicating means continually advancing in response to alternate advances of said members, the control means being constructed to vary the movement of the indicating means throughout each interval in accordance with

the variations in ratio between propeller speed and distance traveled up to the current speed of the propeller.

20

45. In a ship's instrument an indicator, means including an electromagnet for operating said indicator, the circuit leading to said electromagnet having two branches, means in each branch for intermittently closing the circuit to said electromagnet, said means being controlled by the speed of the ship's propeller, and means actuated at predetermined intervals for alternately rendering said circuit closing means inoperative.

25

Signed by me at Boston, Massachusetts, this 18th day of August, 1919.

GEORGE WALKER.
